UNITED STATES PATENT OFFICE.

CHARLES N. BARTON, OF INDIANAPOLIS, INDIANA.

TICKET-HOLDER.

1,302,624.

Specification of Letters Patent.

Patented May 6, 1919.

Application filed August 7, 1916. Serial No. 113,590.

To all whom it may concern:

Be it known that I, CHARLES N. BARTON, a citizen of the United States, residing at Indianapolis, in the county of Marion and 5 State of Indiana, have invented a new and useful Ticket-Holder, of which the following is a specification, reference being had to the accompanying drawings and to the letters and figures of reference marked thereon.

10 This invention relates to a container for card-board tickets and more particularly for tickets that are commonly used in the payment of fares on street cars, the invention having reference more particularly to a 15 ticket-holder that is suitable to be carried in the pocket of a passenger or in a handbag.

An object of the invention is to provide a 20 ticket-holder of the above-mentioned character that shall be so constructed as to be simple and reliable and be adapted to be held and operated in one hand, so as to enable passengers when carrying articles in one hand to readily produce a ticket for passage by means of the other hand. Another 25 object is to provide a ticket-holder that shall be so constructed as to accommodate a large number of tickets and eject the tickets without failure from either a large or a small pack thereof. A further object is to 30 provide a ticket-holder that shall be adapted to be adjusted without requiring a tool or instrument for the purpose.

With the above-mentioned and other objects in view, the invention consists in a 35 ticket-holder having certain novel features of construction and an improved ejector; the invention consisting further in the parts and combinations and arrangements of parts as hereinafter particularly described and 40 further defined in the accompanying claim.

Referring to the drawings,—Figure 1 is a perspective view of the improved ticket-holder with a ticket projecting therefrom. Fig. 2 is a rear end view of the ticket-holder. 45 Fig. 3 is a longitudinal sectional view of the ticket-holder approximately central thereof. Fig. 4 is a transverse section approximately on the line IV—IV of Fig. 3. Fig. 5 is a perspective view of the improved ejector, and Fig. 6 is a top plan of the holder case 50 with its door partially open.

Similar reference characters on the different figures of the drawings indicate like parts or features of construction herein referred to.

A practical embodiment of the invention comprises a box-like case which is most cheaply made of sheet metal suitably bent to form corners, the case comprising a bottom 1, sides 2 and 3, a top composed of two 60 portions 4 and 5 formed of the end portions of the sheet and suitably joined together, as by electric welding or soldering, and also a front end 6 formed integrally with one end of the bottom 1 secured between and to the 65 sides 2 and 3, the end being slightly less in height than the sides so as to provide a slot 7 adjacent to the top of the case from which to deliver the tickets one at a time. The opposite end of the bottom 1 has hinge members 8 and 9 thereon that are provided with a hinge pin 10 which preferably extends through the sides 2 and 3. The rear end of the top of the case has a recess 11 which is above the hinge pin, and the top has also an 70 upward extending catch portion 12 that is adjacent to the recess and formed by pressing a portion of the metal of the case upward. The middle portion of the top of the case has a longitudinal slot 13 therein. The 75 rear end of the case is provided with a door 14 which has a hinge member 15 that is connected to the hinge pin 10, the door being fitted between the sides 2 and 3 and also between the bottom and the top of the case. 80 The middle of the top of the door is provided with a projection 16 that normally extends into the recess 11 and it has an elastic 85 clasp 17 thereon that extends flatwise upon the top of the case. The clasp has an upwardly-bulged portion 18 to receive the projection 12 to hold the door in closed position, and the clasp has an upwardly-extending 90 end portion 19 to be engaged by a finger of the operator to release the clasp in order to 95 open the door. A guide plate 20 is arranged upon the top of the case and covers the slot 13. The guide plate is provided with a knob 21 having a base collar 22 that is seated upon the guide plate and preferably secured thereto, the knob having a squared shank 23 that extends through the guide plate and also through the slot 13, the shank being arranged to slide in the slot longitudinally 100 of the case and prevent rotation of the guide plate. The shank has an extension 24 to which an ejector plate 25 is secured so as to operate against the under side of the top of the case, the ejector plate having an aperture 26 to receive the shank extension. The 105 110

ejector plate has two elastic fingers 27 and 28 on the ends of which are pointed teeth 29 and 30 respectively to engage a ticket when the ejector plate is moved toward the slot 7, the teeth extending slightly downward and toward the end 6 of the case, so that they slide upon the ticket when moved in the reverse direction.

A collapsible helical spring is employed 10 which has a smaller end coil 31 removably seated upon the bottom 1 of the case and its largest end coil 32 arranged uppermost, the end portion 33 of the larger coil being arranged in proximity to the front end 6 of 15 the case. A follower plate 34 is permanently secured to the larger coil of the spring, the plate being but slightly smaller than the bottom or top of the case, and its rear end portion has a downwardly extending curved 20 guide 35 which serves to guide the tickets upon the follower plate when inserting the tickets into the case and also constitutes a finger hold for withdrawing the follower plate when desired from the case. The 25 larger coil of the spring has a bearing with the middle portion of the follower plate, and the end portion 33 bears against the forward portion of the follower plate adjacent to the front 6 so as to exert force to 30 always push up the forward end of the follower plate with slightly greater force than that exerted under the middle portion of the plate. A package of tickets 36, 36' is supported upon the follower plate and the uppermost one of the tickets is always pressed 35 upward against the ejector while the forward end of the ticket is pressed against the top of the case adjacent to the slot 7.

In practical use the passenger holds the 40 case in one hand and with the thumb of the hand pushes the knob 21 forward with the result that the teeth of the ejector engage the uppermost ticket and push it partially out of the slot 7. The knob may be quickly retracted if desired and again pushed forward with the result that the ticket is further projected and if then presented to the ticket taker the latter may readily withdraw the ticket from the case; or the passenger may repeatedly operate the knob 45 until the ticket is completely ejected from the case. After the uppermost ticket has been delivered the package of tickets is automatically elevated to permit the delivery of 50 the next succeeding ticket. In some cases the case may be filled with a large number 55

of tickets which in the course of time may over-tax the spring and slightly impair its usefulness which however may readily be restored in a well known manner, the follower plate 34 and the spring being withdrawn from the case after opening the door 14, after which the spring may be drawn apart to increase its effective length, after which the parts are again inserted into proper position in the case. The adjustment 60 may be desirable when comparatively few tickets are to be subsequently placed in the holder in order that they may be pushed upward with sufficient force to bring the tickets 65 successively against the ejector to insure proper action of the latter.

Having thus described the invention, what is claimed as new is—

In a ticket-holder of the character described, the combination with a case bottom and sides and a front end and also a top extending above the front end at a distance therefrom, the bottom and the top being each equal in length with each of the sides, 75 the middle portion of said top having a relatively short guide slot therein, of a knob shank movable in said slot and having an extension on its inner end that is diametrically smaller than the body of the shank, an 80 ejector plate secured on said extension and having two long elastic fingers thereon that are supported at all times relatively nearer to said front end than to the opposite end of said top, each finger having a tooth thereon extending downwardly toward said front end, a guide plate on said top that is appreciably longer than said slot and constantly covering the slot, the guide plate receiving 85 a portion of said shank, a knob rigid on 90 said shank and having a portion bearing upon said guide plate, a coil spring on said bottom adjacent to said front end, and a follower plate between said sides that is relatively shorter in length than said top 95 and extending at one end to said front end of the case, the portion of said follower plate adjacent to said front end being secured to the top of said spring, the opposite end of said follower plate extending downwardly toward said bottom.

In testimony whereof, I affix my signature in presence of two witnesses.

CHARLES N. BARTON.
